UNITED STATES PATENT OFFICE.

RONALD A. McCANN, OF SWISSVALE, PENNSYLVANIA, ASSIGNOR TO UNION SWITCH & SIGNAL COMPANY, OF SWISSVALE, PENNSYLVANIA, A CORPORATION OF PENNSYLVANIA.

RAILWAY-TRAFFIC-CONTROLLING SYSTEM.

1,363,257.

Specification of Letters Patent. Patented Dec. 28, 1920.

Application filed June 26, 1919. Serial No. 306,776.

To all whom it may concern:

Be it known that I, RONALD A. McCANN, a citizen of the United States, residing at Swissvale, in the county of Allegheny and State of Pennsylvania, have invented certain new and useful Improvements in Railway-Traffic-Controlling Systems, of which the following is a specification.

My invention relates to railway traffic controlling systems, and particularly to systems of the type wherein alternating current or currents are supplied to the track rails, and the cars or trains are provided with governing apparatus which is controlled by such current or currents in the rails.

In one system of the type mentioned, it has been proposed to employ the usual track circuit current, that is, the current which energizes the track relays, as one of the currents for controlling the train-carried governing apparatus, the train governing apparatus being controlled by this current through the medium of receiving appliances at the front end of the train. When this is done, it is obvious that the source of track circuit current must always be connected across the track rails ahead of a train.

In the case of a double track railroad wherein traffic on each track normally moves in one direction only, this requirement is readily met in so far as movements in the normal direction are concerned, because the source of track circuit current for each section of track can then be connected across the rails at the exit end of the section, this being in fact in accordance with standard practice in automatic block signaling. On roads of this kind, however, it is sometimes necessary for trains to move in opposition to the normal direction of traffic, and in such instances with only the trackway apparatus thus far mentioned the train would not receive track circuit current. One feature of my invention is the provision of means located in the trackway and set into operation by a train moving against the normal direction of traffic for connecting an auxiliary source of track circuit current across the rails of each section at what is normally the entrance end of the section.

In systems of this type it has also been proposed to supply a second, or "line circuit current", to the track rails in such manner that it flows through the two rails in

multiple, which current coacts with the track circuit current to control the train governing apparatus. This line circuit current is supplied to only the rear portion of each section when the section next in advance is occupied, and so it follows that when a train moving against the normal direction of traffic enters a section it will not receive line circuit current until the rear end of the train has passed out of the adjacent section. Another feature of my invention is the provision of means for supplying line circuit current to the rails of a section throughout the entire section, regardless of conditions in any other section, when a train moving against the normal direction of traffic enters the section.

I will describe one form of trackway apparatus embodying my invention, and will then point out the novel features thereof in claims.

The accompanying drawing is a diagrammatic view showing one track of a double track railway equipped with trackway apparatus embodying my invention.

Referring to the drawing, the reference characters 2 and 2^a designate the two traffic rails of a railway track F over which traffic normally moves only in the direction indicated by the arrow. These rails are divided by insulated joints 3 into a plurality of successive sections, of which only two complete sections B—C and C—D are shown in the drawing.

Each track section is provided with a track circuit comprising two track relays and a source of track circuit current. Considering section C—D, for example, two track relays T⁵ and T⁶ are connected across the track rails adjacent the exit and entrance ends of the section respectively, and the secondary of a transformer E^c is also connected across the rails of this section adjacent the exit end. The primary of transformer E^c is connected with the secondary of a transformer U^c through a pole-changer P^c operated as hereinafter explained. The primary of transformer U^c as well as the primaries of certain other transformers U^b and U^d, are connected with a suitable source of alternating current which is not shown in the drawing. The track relay T⁵ at the exit end of the section is constantly connected with the rails of the section, but the track relay T⁶ at the entrance end is at

times disconnected from the rails by a relay J^D and the secondary of a transformer H^D is then connected across the rails through the front contacts of relay J^D . In other words, track relay T^e or transformer H^D is connected with the rails of section C—D adjacent the entrance end thereof, according as relay J^D is deenergized or energized. The primary of transformer H^D is connected with the secondary of transformer U^D . The connection between the secondary of transformer E^c and the track rails includes a back contact 46 of a relay K^c , so that when this relay is energized transformer E^c is disconnected from the rails of the section. The control of relays K^c and J^D will be explained hereinafter.

Each track section is provided with track circuit apparatus similar to that just described for section C—D.

Located adjacent the entrance end of each section is a signal which is designated by the reference character S with an exponent corresponding to the location, each of which signals is adapted to indicate stop, caution and proceed. Each signal is controlled by the track relay at the entrance end of the corresponding section. Considering signal S^D , for example, the caution indication circuit is from the secondary of transformer U^D , through wires 4, 5 and 6 right-hand point of contact 7 of track relay T^e , wire 15, operating mechanism of signal S^D , wire 9, right-hand point of contact 11 of track relay T^e , and wires 12 and 13 to the secondary of transformer U^D . The proceed indication circuit for this signal is from the secondary of transformer U^D , through wires 4, 5 and 6, left-hand point of contact 7, wire 8, operating mechanism of signal S^D , wire 9, right-hand point of contact 11, and wires 12 and 13 to the secondary of transformer U^D . It will be seen, therefore, that signal S^D will indicate proceed when track relay T^e is energized in such direction that its contacts 7 and 11 are swung to the left, which direction I will term the normal direction of energization of this relay, and that this signal will indicate caution when track relay T^e is energized in the other or reverse direction. Relay T^e is energized in normal direction when track circuit current of normal polarity is supplied to the rails of section C—D by transformer E^c . When current of reverse polarity is supplied to the rails of this section by transformer E^c , track relay T^e is energized in reverse direction, so that its contacts 7 and 11 are swung to the left, causing signal S^D to indicate caution.

The polarity of the current supplied to the track circuit for section C—D is controlled by pole-changer P^c , which is operated by signal S^c in such manner that the track circuit current is of normal polarity when signal S^c indicates proceed or caution, and

of reverse polarity when this signal indicates stop.

Although as here shown track relay T^e comprises only one winding, it is, of course, understood that inasmuch as this relay is operated by alternating current, it comprises a second winding constantly supplied with current from either transformer H^D or transformer U^D . This second winding is omitted from the drawing for the purpose of simplification. The same thing is true as to relays T^2 and T^4 .

The control of the signal and of the polarity of the track circuit current for each section is the same as for section C—D.

Line circuit current is supplied to the track rails of each section through the medium of resistances 20, 21 and 22, which are connected across the rails of the section at the entrance end of the section, intermediate point in the section, and the exit end of the section, respectively. Again considering section C—D specifically, line circuit current is constantly supplied to the rails between resistances 20 and 21 when the section is occupied, the circuit being from the left-hand terminal of the secondary of transformer F^D , through contact 16 of relay T^e , wire 17 to the middle point of resistance 20, thence through the two rails 2 and 2^a in multiple to resistance 21, and from the middle point of this resistance through wires 18 and 19 to the secondary of transformer F^D . The primary of transformer F^D is connected with the secondary of transformer U^D . Contact 16 is closed only when relay T^e is deenergized, and, consequently, line circuit current is supplied to the circuit just traced only when section C—D is occupied by a train, but at such times this circuit is always closed regardless of traffic conditions in advance of the section. Line circuit current is also supplied at times to the rails of section C—D between resistances 21 and 22, the normal circuit being from the left-hand terminal of the secondary of transformer G^c , through wires 23 and 24, contact 25 operated by signal S^c , wire 26 to the middle point of resistance 22, rails 2 and 2^a in multiple to resistance 21, and from the middle point of this resistance through wires 18 and 42 to the secondary of transformer G^c . Contact 25 is closed when signal S^c indicates proceed or caution, but open when this signal indicates stop. It will be seen, therefore, that so far as the circuit just traced is concerned, line circuit current is supplied to section C—D between points 21 and 22 only when the signal for the next section in advance indicates proceed or caution. The path for the line circuit current for this portion of section C—D is provided with a branch, however, around contact 25 of signal S^c , which branch passes from wire 23, through wire 27, contact 28 of relay K^c , and wire 29 to wire 26. It follows

that when relay K^c is energized, line circuit current is supplied to the rails of section C—D between resistances 21 and 22 regardless of the position of signal S^c .

5 The line circuit apparatus for each section is the same as that just explained for section C—D.

Again considering section C—D, relays K^c and J^p are provided with a pick-up circuit, which is as follows: from the left-hand terminal of the secondary of transformer U^p , through wires 4, 5, 30, 31 and 31^a, contact 10 operated by signal S^p , wire 32, winding of relay J^p , wire 33, back contact 15 34 of track relay T^s , wire 35, winding of relay K^c , and wire 36 to the secondary of transformer U^p . It will be seen that this circuit is closed only when contact 10 and track relay contact 34 are simultaneously 20 closed. It follows, therefore, that the circuit will not be closed when a train moves in the direction indicated by the arrow, because contact 10 will open immediately upon the entrance of such a train into section 25 C—D, whereas track relay contact 34 will not close until the train has proceeded a considerable distance into the section. When a train moving in the direction opposite to that indicated by the arrow enters 30 the section, however, it will immediately open track relay T^s , so that contact 34 of this relay will close before signal-operated contact 10 has time to open. A train moving in this direction, therefore, will cause 35 relays K^c and J^p to become energized. As soon as relay J^p closes, a branch for this circuit around contact 10 is closed, which branch is from wire 30, through wire 39, contact 40 of relay J^p , and wire 41 to wire 40 32. It follows, therefore, that when relays K^c and J^p have once become closed, they will remain closed as long as track relay contact 34 remains closed, that is, until the entire train has passed out of section C—D.

45 Before explaining the operation of the system as a whole it should be pointed out that the trackway apparatus here shown is intended for coöperation with train-carried governing apparatus which operates in the following manner: When the train is on a portion of track which is supplied with track circuit current of normal polarity and also with line circuit current, the governing apparatus permits the train to travel at high speed, such as 65 miles per hour. When the portion of track occupied by the train is supplied with track circuit current of reverse polarity and also with line circuit current, the governing apparatus prevents 50 the train from proceeding at more than an intermediate speed, such as 35 miles per hour, but when the train enters a portion of track from which the supply of either track circuit or line circuit current is discontinued, the governing apparatus prevents the

train from proceeding at more than a low speed such as 10 miles per hour. One form of governing apparatus which will coöperate in this manner with the trackway apparatus here shown, is illustrated and described in an application filed in the United States Patent Office by Lloyd V. Lewis on Nov. 1, 1918, Serial No. 263607, for railway traffic controlling systems. 70

The operation of the entire apparatus is 75 as follows:

I will first assume that the stretch of track shown in the drawing is unoccupied, and that a train moving in the direction indicated by the arrow enters the stretch. As 80 this train enters section C—D, it deenergizes track relay T^s , so that contacts 7, 11 and 16 move to their intermediate positions. The opening of contacts 7 and 11, of course, causes signals S^p to move to the stop position. The movement of contact 16 to its intermediate position closes the line circuit for the rear portion of section C—D, so that line circuit current is supplied to the rails of this section between resistances 20 and 21. 85 Inasmuch as signal S^c is in the proceed position, track circuit current of normal polarity is supplied to the rails of section C—D from transformer E^c . Line circuit current is also supplied to the rails of this 90 section between resistances 21 and 22, because signal S^c is in the proceed position. It follows, therefore, that the train can proceed through section C—D at 65 miles per hour or less. The operation of the apparatus in section B—C is the same as that of the apparatus in section C—D, and hence 95 it will be understood without further explanation. 100

I will now assume that while the first train is in section B—C, a second train enters section C—D. Signal S^c is then at stop, so that track circuit current of reverse polarity is supplied to the rails of section C—D. Contact 25 operated by signal S^c is 110 open, so that line circuit current is not supplied to section C—D between resistances 21 and 22. As the second train passes the point D, it will receive line circuit current and it will also receive track circuit current 115 of reverse polarity, so that this train will incur a brake application if it exceeds a speed of 35 miles per hour while between resistances 20 and 21. After passing resistance 21, the train will cease to receive 120 line circuit current and consequently it will incur a brake application if it exceeds 10 miles per hour. If this second train passes signal S^c while the latter is still at stop it will fail to receive track circuit current because such current is shunted by the wheels and axles of the first train, and consequently, the second train will still be compelled to proceed at a speed not exceeding 125 10 miles per hour. 130

I will now assume that, owing to an emergency condition, it is necessary for a train to pass over the stretch of track shown in the drawing in the direction opposite to that indicated by the arrow, and I will furthermore assume that such train is in section B—C and is about to enter section C—D. Signal S^D is, of course, at stop, so that signal S^D is in the caution position. As this train enters section C—D, it immediately opens track relay T^s, and since contact 10 is still closed, relays K^c and J^D will become energized. Relay K^c then disconnects transformer E^c from the track rails; whereas relay J^D disconnects track relay T^s from the rails, and connects transformer H^D with the rails, at the right-hand end of the section. Relay K^c also closes the shunt around contact 25 in the line circuit for the portion of the section between resistances 21 and 22, so that line circuit current is supplied to this part of the section. Track relay T^s of course becomes deenergized, so that line circuit current is also supplied to the section between resistances 20 and 21. Track circuit current is now supplied to the rails from transformer H^D, and the current thus supplied is of normal polarity, so that the train can proceed through section C—D at full speed, that is, at 65 miles per hour or less, without incurring a brake application. When the rear end of this train passes out of section C—D, track relay T^s will become energized by virtue of the current supplied to the rails by transformer H^D. The closing of track relay T^s will open the circuit for relays K^c and J^D, so that these relays will then become deenergized. The opening of relay J^D will disconnect transformer H^D from, and connect relay J^D with, the rails of the section; the opening of relay K^c will again connect transformer E^c with the track rails. Relay T^s will then become energized by virtue of current from transformer E^c, so that signal S^D will return to the proceed position (or to the caution position if section B—C is occupied).

It will be noted that an impedance 43 is interposed between track rail 2^a and the winding of track relay T^s. When relay K^c is energized, this impedance is shunted by a low resistance path which passes from point 44, through wire 45, front point of contact 46 of relay K^c, and wire 49 to point 45. The impedance 43 is, therefore, shunted out of the track circuit when relay K^c is energized. The reason for this is as follows:

When the track circuit for section C—D is in normal condition, that is, when the parts are as shown in the drawing, transformer E^c is connected across the rails at the same point as track relay T^s. The impedance 43 is desirable at such time in order to avoid over-energization of relay T^s, and under-energization of relay T^s. When, how-

ever, the track circuit arrangement is reversed; that is, when transformer E^c is disconnected from the rails and transformer H^D is connected with the rails, it would be undesirable to leave the impedance 43 in series with relay T^s, because an undue amount of energy would then be required from transformer H^D to cause track relay T^s to close after a train moving toward the right passes out of the section. A low resistance path around this impedance is provided, therefore, to shunt out the impedance while the track circuit is reversed, with the result that only the normal amount of energy is required from transformer H^D to energize relay T^s when the train moving toward the right leaves the section.

Although in certain of the accompanying claims I have referred specifically to track section C—D, it is understood that this is done only for the sake of clearness, and that all such claims are readable equally well on the apparatus shown in track section B—C.

Although I have herein shown and described only one form of trackway apparatus embodying my invention, it is understood that various changes and modifications may be made therein within the scope of the appended claims without departing from the spirit and scope of my invention.

Having thus described my invention, what I claim is:

1. In combination, a section of railway track over which traffic normally moves in one direction only, a track relay normally connected across the rails adjacent the entrance end of the section and a source of current located adjacent the same end, a second track relay constantly connected across the rails, adjacent the exit end of the section and a second source of current normally connected across the rails adjacent the exit end of the section; a signal located adjacent the entrance end of said section and controlled by the track relay at the same end; and means controlled by said signal and by said second track relay and operating when a train moving in opposition to the normal direction of traffic enters said section to disconnect said first track relay from the track rails, to connect said first source of current with the track rails, and to disconnect said second source of current from the track rails.

2. In combination, a section of railway track over which traffic normally moves in one direction only, two track relays T^s and T^s adjacent the entrance and exit ends of said section respectively, the latter relay being constantly connected with the track rails, a signal S^D for said section controlled by said track relay T^s, two sources of alternating current H^D and E^c adjacent the entrance and exit ends of said section respectively, the latter being normally con-

- 5 nected with the rails of said section, a relay J^p for connecting track relay T^e or source H^p with the track rails according as relay J^p is deenergized or energized, a relay K^c for disconnecting source E^c from the track rails when the relay is energized, a contact 10 operated by signal S^p and closed or open according as the signal indicates proceed or stop, a circuit including relays J^p and K^c , a back contact of track relay T^e and said contact 10, and a branch for said circuit around contact 10 and including a front contact of relay J^p .
3. In combination, a section of railway track over which traffic normally moves in one direction only, two track relays T^e and T^s adjacent the entrance and exit ends of said section respectively, the latter relay being constantly connected with the track rails, a signal S^p for said section controlled by said track relay T^e , two sources of alternating current H^p and E^c adjacent the entrance and exit ends of said section respectively, the latter being normally connected with the rails of said section, a relay J^p for connecting track relay T^e or source H^p with the track rails according as relay J^p is deenergized or energized, a relay K^c for disconnecting source E^c from the track rails when the relay is energized, and means controlled by said signal and by said track relay T^e and operating when a train moving in opposition to the normal direction of traffic enters said section to energize said relays K^c and J^p and to keep them energized until such train leaves the section.
4. In combination, a section of railway track over which traffic normally moves in one direction only, a track relay and a source of current at the entrance end of said section the former being normally connected with the rails of the section, a second source of current connected with the rails of said section at the exit end, a signal located adjacent the entrance end of said section and controlled by said track relay, and means controlled by said signal and operating when a train moving in opposition to said normal direction of traffic enters the section to disconnect said track relay from the rails of the section and connect said first-mentioned source of current with said rails.
5. In combination, a section of railway track over which traffic normally moves in one direction only, a track relay and a source of current at the entrance end of said section the former being normally connected with the rails of the section, a second source of current connected with the rails of said section at the exit end, a signal located adjacent the entrance end of said section and controlled by said track relay, and means controlled by a normally deenergized relay J^p arranged
- when energized to disconnect said track relay from the rails of said section and to connect said first-mentioned source of current with said rails, means controlled by said signal and operating when a train moving in opposition to said normal direction of traffic enters said section to energize said relay J^p , and means for keeping said latter relay energized until such train leaves the section.
6. In combination, a section of railway track over which traffic normally moves in one direction only, a source of current connected with the track rails adjacent the exit end of the section, a second source of current adjacent the entrance end of the section but normally disconnected from the rails, a signal located adjacent the entrance end of said section and controlled by traffic conditions in the section, and means controlled by said signal and operating when a train moving in opposition to said normal direction of traffic enters the section to connect said second source of current with the rails of the section.
7. In combination, a section of railway track over which traffic normally moves in one direction only, a line circuit including the two track rails in multiple from the entrance end of the section to an intermediate point in the section, means for supplying current to said circuit, a second line circuit including the two track rails in multiple from said intermediate point to the exit end of the section, means controlled by traffic conditions in advance of said section for supplying current to said second line circuit, and means controlled by a train entering said section in opposition to the normal direction of traffic for supplying current to said second line circuit regardless of traffic conditions extraneous to the section.
8. In combination, a section of railway track over which traffic normally moves in one direction only, a line circuit including the two track rails in multiple from the entrance end of the section to an intermediate point in the section, means for supplying current to said circuit, a second line circuit including the two track rails in multiple from said intermediate point to the exit end of the section, means controlled by traffic conditions in advance of said section for supplying current to said second line circuit, and means controlled by a train entering said section in opposition to said normal direction of traffic for removing said last-mentioned means from control by traffic conditions in advance of the section.
9. In combination, a section of railway track over which traffic normally moves in one direction only, a line circuit including the two track rails in multiple from the entrance end of the section to an intermediate point in the section, means for supplying current

to said circuit, a second line circuit including the two track rails in multiple from said intermediate point to the exit end of the section, means controlled by traffic conditions in advance of said section for supplying current to said second line circuit, a normally deenergized relay, means controlled by said relay when energized for removing said last-mentioned means from control by traffic conditions in advance of the section, and means controlled by a train entering said section in opposition to said normal direction of traffic for energizing said relay.

15. 10. In combination, a section of railway track over which traffic normally moves in one direction only, means for supplying line circuit current to the two rails of said section in multiple from the entrance end to an intermediate point in the section or from the entrance end to the exit end according to traffic conditions in advance of the section, and means controlled by a train entering said section in opposition to the normal direction of traffic for removing said means from control by traffic conditions in advance of the section and supplying line circuit current to the rails throughout the length of the section.

30. 11. In combination, a railway track over which traffic normally moves in one direction only, means for dividing said track into a plurality of successive sections, a signal for each section located adjacent the entrance end of the section, means for each section for supplying line circuit current to the two track rails of the section in multiple from the entrance end of the section to an intermediate point in the section regardless of traffic conditions in advance of the section, means for each section controlled by the signal for the section next in advance for supplying line circuit current to the two track rails of the section in multiple from said intermediate point to the exit end of the section when said signal indicates proceed but not when said signal indicates stop, and means for each section controlled by a train entering the section in opposition to the normal direction of traffic for removing said last-mentioned means from control by the signal for the section in advance.

12. 55. In combination, a railway track over which traffic normally moves in one direction only, means for dividing said track into a plurality of successive sections, a signal for each section located adjacent the entrance end of the section, means for each section for supplying line circuit current to the two track rails of the section in multiple from the entrance end of the section to an intermediate point in the section regardless of traffic conditions in advance of the section, means for each section controlled by the signal for the section next in advance

for supplying line circuit current to the two track rails of the section in multiple from said intermediate point to the exit end of the section when said signal indicates proceed but not when said signal indicates stop, a normally deenergized relay for each section, means controlled by said relay when energized for removing said last-mentioned means from control by the signal for the section next in advance, and means for each section controlled by a train entering the section in opposition to said normal direction of traffic for energizing the relay for such section.

13. 13. In combination, a railway track over which traffic normally moves in one direction only, means for dividing said track into a plurality of successive sections, a signal for each section located adjacent the entrance end thereof, a line circuit for each section including the track rails of the section in multiple from the entrance end of the section to an intermediate point in the section, means for supplying current to said circuit regardless of traffic conditions in advance of the section, a second line circuit for each section including the track rails of the section in multiple from said intermediate point to the exit end of the section and including a contact operated by the signal for the section next in advance which contact is closed when the signal indicates proceed but not when the signal indicates stop, a branch for said second line circuit for each section around said signal-operated contact, and means for each section controlled by a train entering the section in opposition to the normal direction of traffic for closing the branch for the second line circuit for such section.

14. 14. In combination, a section of railway track over which traffic normally moves in one direction only, a signal located adjacent the entrance end of said section and governing traffic through the section, a track circuit for said section including a track relay located adjacent the exit end of the section, means for supplying line circuit current to the two track rails of said section in multiple from the entrance end of the section to an intermediate point in the section or from the entrance end of the section to the exit end of the section according to traffic conditions in advance of the section, and means controlled by said signal and by said track relay and operating when a train moving in opposition to said normal direction of traffic enters said section for removing said means from control by traffic conditions in advance of the section.

15. 15. In combination, a section of railway track over which traffic normally moves in one direction only, a source of current normally connected with the track rails adjacent the exit end of the section, a second

- source of current adjacent the entrance end of the section, a track relay connected with the rails adjacent the exit end of the section, and a second track relay normally connected 5 with the rails adjacent the entrance end of the section, a signal located adjacent the entrance end of said section and controlled by said second track relay, means controlled by traffic conditions in advance of said section for supplying line circuit current to the two track rails in multiple from the entrance end of the section to an intermediate point in the section or from the entrance end to the exit end of the section; and means controlled 10 by the first track relay and by said signal and operating when a train moving in opposition to the normal direction of traffic enters the section to disconnect said second track relay from the rails, and to connect said second source of current with the rails adjacent the entrance end of the section and to supply line circuit current to the two track rails in multiple throughout the entire section regardless of traffic conditions in advance of the section. 15
16. In combination, a section of railway track over which traffic normally moves in one direction only, a line circuit extending from the entrance end of the section to an intermediate point in the section and including a source of alternating current, a second line circuit extending from said intermediate point to the exit end of the section, means controlled by traffic conditions in advance of said section for supplying current to said second line circuit, and means controlled by a train entering said section in opposition to the normal direction of traffic for supplying current to said second line circuit regardless of traffic conditions extraneous to the section. 20
17. In combination, a section of railway track over which traffic normally moves in one direction only, a line circuit extending from the entrance end of the section to an intermediate point in the section and including a source of alternating current, a second line circuit extending from said intermediate point to the exit end of the section, means controlled by traffic conditions in advance of said section for supplying current to said second line circuit, and means controlled by a train entering said section in opposition to said normal direction of traffic for removing said last-mentioned means from control by traffic conditions in advance of the section. 25
18. In combination, a section of railway track over which traffic normally moves in one direction only, a line circuit extending from the entrance end of the section to an intermediate point in the section and including a source of alternating current, a second line circuit extending from said intermediate point to the exit end of the section, means controlled by traffic conditions in advance of said section for supplying current to the two track rails in multiple from the entrance end to an intermediate point in the section or from the entrance end to the exit end of the section; and means controlled by the first track relay and by said signal and operating when a train moving in opposition to the normal direction of traffic enters the section to disconnect said second track relay from the rails, and to connect said second source of current with the rails adjacent the entrance end of the section and to supply line circuit current to the two track rails in multiple throughout the entire section regardless of traffic conditions in advance of the section, means for each section located adjacent the entrance end of the section, means for supplying line circuit current to the section from the entrance end of the section to an intermediate point in the section regardless of traffic conditions in advance of the section, means for each section controlled by the signal for the section next in advance for supplying line circuit current to the section from said intermediate point to the exit end of the section when said signal indicates proceed but not when said signal indicates stop, and means for each section controlled by a train entering the section in opposition to the normal direction of traffic for removing said last-mentioned means from control by the signal for the section in advance. 30
21. In combination, a railway track over which traffic normally moves in one direction only, means for dividing said track into a plurality of successive sections, a signal for each section located adjacent the entrance end of the section, means for each section for supplying line circuit current to the section from the entrance end of the section to an intermediate point in the section regardless of traffic conditions in advance of the section, means for each section controlled by the signal for the section next in advance for supplying line circuit current to the section from said intermediate point to the exit end of the section when said signal indicates proceed but not when said signal indicates stop, a normally deenergized relay for each section, means controlled by said relay when energized for removing said last-mentioned means from control by the signal for the section in advance. 35

- section next in advance, and means for each section controlled by a train entering the section in opposition to said normal direction of traffic for energizing the relay for such 5 section.
22. In combination, a railway track over which traffic normally moves in one direction only, means for dividing said track into a plurality of successive sections, a signal 10 for each section located adjacent the entrance end thereof, a line circuit for each section extending from the entrance end of the section to an intermediate point in the section, means for supplying current to said 15 circuit regardless of traffic conditions in advance of the section, a second line circuit for each section extending from said intermediate point to the exit end of the section and including a contact operated by the signal 20 for the section next in advance which contact is closed when the signal indicates proceed but not when the signal indicates stop, a branch for said second line circuit for each section around said signal-operated contact, 25 and means for each section controlled by a train entering the section in opposition to the normal direction of traffic for closing the branch for the second line circuit for such section.
30. 23. In combination, a section of railway track over which traffic normally moves in one direction only, a signal located adjacent the entrance end of said section and governing traffic through the section, a track circuit 35 for said section including a track relay located adjacent the exit end of the section, means for supplying line circuit current to said section from the entrance end of the section to an intermediate point in the section 40 or from the entrance end of the section to the exit end of the section according to traffic conditions in advance of the section, and

means controlled by said signal and by said track relay and operating when a train moving in opposition to said normal direction of 45 traffic enters said section for removing said means from control by traffic conditions in advance of the section.

24. In combination, a section of railway track over which traffic normally moves in one direction only, a source of current normally connected with the track rails adjacent the exit end of the section, a second source of current adjacent the entrance end of the section, a track relay connected with the rails adjacent the exit end of the section, and a second track relay normally connected with the rails adjacent the entrance end of the section, a signal located adjacent the entrance end of said section and controlled by 60 said second track relay, means controlled by traffic conditions in advance of said section for supplying line circuit current to the section from the entrance end of the section to an intermediate point in the section or from 65 the entrance end to the exit end of the section; and means controlled by the first track relay and by said signal and operating when a train moving in opposition to the normal direction of traffic enters the section to disconnect said second track relay from the rails, and to connect said second source of current with the rails adjacent the entrance end of the section and to supply line circuit 70 current to the section throughout the entire 75 section regardless of traffic conditions in advance of the section.

In testimony whereof I affix my signature in presence of two witnesses.

RONALD A. McCANN.
